See application file for complete search history.

The ornamental design for a dispensing nipple, as shown.

DESCRIPTION

FIG. 1 is a perspective view of a dispensing nipple illustrating our new design;

FIG. 2 is a front side elevational view of the design of FIG. 1; FIG. 3 is a back side elevational view of the design of FIG. 1; FIG. 4 is a left side elevational view of the design of FIG. 1; FIG. 5 is a right side elevational view of the design of FIG. 1; FIG. 6 is a top planar view of the design of FIG. 1; and, FIG. 7 is a bottom planar view of the design of FIG. 1.

The broken line showing of a dispenser cartridge is included for the purpose of illustrating and forms no part of the claimed design.
